UNITED STATES PATENT OFFICE.

HERMAN J. OSTDIÉK, OF MINNEAPOLIS, MINNESOTA, AND MARY E. HANKE, OF OSHKOSH, WISCONSIN.

MOP.

Application filed March 24, 1923. Serial No. 627,279.

To all whom it may concern:

Be it known that we, HERMAN J. OSTDIÉK and MARY E. HANKE, citizens of the United States, residing, respectively, at Minneapolis and Oshkosh, in the counties of Hennepin and Winnebago and States of Minnesota and Wisconsin, have invented certain new and useful Improvements in Mops; and we do hereby declare the following to be a full, clear, and exact description of the invention, such as will enable others skilled in the art to which it appertains to make and use the same.

Our invention provides an extremely simple, cheap and highly efficient mop adapted to be used either as a dry, wet or oiled mop, and generally stated, the invention consists of the novel construction and arrangement of parts hereinafter described and defined 20 in the claims.

The complete mop comprises a suitable handle, a flexible coiled mop holder, and a swab consisting of a fabric casing and an absorbent body, preferably of cotton cords. 25 A plurality of swabs may be interchangeably used with the common handle and holder, and some of said swabs may be suitable for use as a wet mop, others for use as a dry mop, and still others for use as an oiled 30 mop.

In the accompanying drawings, which illustrate the invention, like characters indicate like parts throughout the several views.

Referring to the drawings:

Fig. 1 is a side elevation of the complete mop, part of the handle stick being broken away;

Fig. 2 is a plan view of the parts shown in Fig. 1, some parts being in section;

Fig. 3 is a plan view of the coiled spring mop holder removed from working position and allowed to assume its natural straight position;

Fig. 4 is a perspective showing the mop swab in the process of construction, but not yet completed; and

Fig. 5 is a perspective with some parts broken away showing the completed swab.

The mop handle is preferably in the form of an ordinary wooden stick 6 preferably cut round and provided at its end with a two-part metal clamping head. This clamping head is preferably made up of two pressed metal plates 7 stamped to form supplemental approximately semi-cylindrical

socket-forming portions 8, and laterally projecting supplemental semi-cylindrical spring clamping portions 9. The bodies of the plates 7 form webs between the socket-forming portions 8 and 9. The socket-forming portions 8 fit the end of the handle stick 6, and nut-equipped bolts 10 are passed therethrough to rigidly clamp said sections onto said stick. Other nut-equipped bolts 11 are passed through the webs of the plates 7.

The swab holder is in the form of a cylindrically formed coiled spring 12 that is naturally straight as shown in Fig. 3, but is adapted to bend into circular form when its ends are inserted into the socket-forming portions 9 of the mop head. The ends of said spring may be readily inserted into said socket-forming portions 9 when the nuts of the bolts 10 and 11 are loosened, but when the said nuts are tightened, the ends of said spring will be tightly clamped to said head, and the said head will be clamped to the handle or stick 6.

The mop swab in itself involves novel features. It is made up of strong cloth or fabric strip 13 and layers of short cords 14. These layers of cords 14 are placed cross-wise of the fabric strip 13 when the latter is straightened out as indicated by dotted lines in Fig. 4, the ends of the cords projecting equally from both sides of the strip. Then the ends of the strip 13 are turned over onto the cords as shown by full lines in Fig. 4, and one or more lines of stitches 15 are sewed through the fabric strip and cords, as shown in Fig. 4. Next, the swab is folded upon itself on the line of the stitches 15 so as to bring both ends of the cords together or in a common group, and then one or more lines of stitches 16 are sewed through the fabric and cords, as shown in Fig. 5, thus leaving an open substantially tubular casing 17 through which the spring holder 12 may be inserted end-wise. The spring 12 is of such length that its ends will project slightly through the ends of the casing 17, and hence be free to be inserted into the socket-forming portions 9 of the mop head. By reference to Fig. 2 it will be noted that the socket-forming portions 9 are bent on the curved line of a circle whose center is at the center of the bent coiled spring 12.

Obviously, the coiled spring affords a very

flexible holder for the swab and will freely bend vertically to adapt itself to a floor angle and may also be readily forced into oval or elongated form, thus adapting the 5 mop to any and all kinds of surfaces and conditions encountered in scrubbing, oiling, or dusting floors or the like.

The cylindrically coiled spring affords the most flexible kind of a resilient form for 10 holding the mop normally in the form of a loop, which loop is adapted to be bent into various different shapes but will resume its normal shape when relieved from pressure. For instance, if the mop is crowded against 15 the wall, it will flatten out to fit the wall, or if forced into a corner, will assume an angular form, but in any case, when released, will, by the spring, be restored to a normal circular or curved looped form.

20 The above described mop, while of simple construction, may be made at very small cost and is highly efficient for the purposes had in view. The swab may be quickly removed or applied and different swabs may 25 be quickly interchanged. When the mop is used as an oiled mop, a certain amount of hard lubricating oil may be inserted into the spring where it will come into contact with the fabric casing and will, by capillary at-

traction, be carried into the cords of the 30 fabric, thereby keeping the swab always properly oiled.

What we claim is:

1. A mop comprising a handle, a head applied to one end of said handle, a resilient cylindrically coiled spring bent to form a loop and having its ends secured to said head, and a swab provided with means whereby it is secured on said spring, and which spring and swab are adapted to be 35 sprung into various different forms but to return to normal shape when relieved from pressure.

2. A mop comprising a handle, a clamping head applied to one end of said handle, a resilient cylindrically coiled spring bent to form a loop and having its ends clamped to said head, and a swab having a casing telescoped onto said coiled spring, and which spring and swab are adapted to be sprung 40 into various different forms but to return to normal shape when relieved from pressure.

In testimony whereof we affix our signatures.

HERMAN J. OSTDIEK.
MARY E. HANKE.
